UNITED STATES PATENT OFFICE

WILLIAM H. LANDMESSER, OF SALT LAKE CITY, UTAH

DESIGN FOR A NOVELTY TOY OR SIMILAR ARTICLE

Application filed May 4, 1932. Serial No. 43,711. Term of patent 7 years.

To all whom it may concern:

Be it known that I, WILLIAM H. LANDMESSER, a citizen of the United States, residing at Salt Lake City, in the county of Salt Lake and State of Utah, have invented a new, original, and ornamental Design for Novelty Toy or Similar Article, of which the following is a specification, reference being had to the accompanying drawing, forming a part thereof.

The figure is a perspective view of a novelty toy, showing my new design.

I claim:

The ornamental design for a novelty toy, or similar article, as shown.

WILLIAM H. LANDMESSER.
